(57) **CLAIM**

The ornamental design for a foldable paper laptop stand for educational task cards, as shown and described.

DESCRIPTION

FIG. 1 is a side perspective view;
FIG. 2 is a side perspective view;
FIG. 3 is a rear perspective view;
FIG. 4 is a bottom perspective view;
FIG. 5 is a side perspective view;
FIG. 6 is a front perspective view; and,
FIG. 7 is a front perspective view.

The design is the overall configuration, shape, ornamentation and pattern of the foldable paper article as shown in the drawings. The nature and intended use of the foldable paper article may be, but is not limited to, a stand for educational task cards.
